UNITED STATES PATENT OFFICE.

S. ANDRAL KILMER, OF BINGHAMTON, NEW YORK.

RAILROAD-JOINT.

SPECIFICATION forming part of Letters Patent No. 363,398, dated May 24, 1887.

Application filed February 24, 1887. Serial No. 928,754. (No model.)

To all whom it may concern:

Be it known that I, S. ANDRAL KILMER, a citizen of the United States, residing at Binghamton, in the county of Broome and State of New York, have invented certain new and useful Improvements in Railroad-Joints; and I do declare the following to be a full, clear, and exact description of the invention, such as will enable others skilled in the art to which it applies to make and use the same, reference being had to the accompanying drawings, and to the letters and figures of reference marked thereon, which form a part of this specification.

Figure 1 is a side view of a rail-joint provided with the invention. Fig. 2 is a sectional view on line $x-x$, Fig. 1. Fig. 3 is a sectional view on line $y-y$, Fig. 2. Fig. 4 is a side view, the fish-plates being removed and the rails apart. Fig. 5 is a perspective view of the adjustable supporter.

This invention relates to improvements in rail-joints for railroads, and has for its object the production of a support for the meeting ends of two rails.

In the construction of rail-joints a necessary looseness of the rails within the fish-plates must be given, so as to allow for the movement of the rails incident upon variation of temperature. As a consequence of this unavoidable looseness there is more or less vertical play of the ends of the rails; also, in cold weather, especially, there is quite a space between the ends of the rails. As the train-wheels pass over these spaces there is of course a point where the lowest part of the rail coinciding with this space virtually has no support. Thus the wheel jumps from the end of one rail to that of the other. As the ends are loose, the wheel first bears down the nearer end, and then jumping from that one, which springs back, strikes the other one and forces it down. This produces the disagreeable "chucking" well known to all travelers, and also beats out the ends of the rails. Now, the present invention, while allowing the needed movement of the rails incident to variation of temperature, effectually prevents the pounding and chucking by giving a support to the ends of the rails by interlocking them in such a manner that they cannot spring vertically

and independent of each other, this invention being an improvement upon similar devices having in view the same object.

In the annexed drawings, the letters A A indicate the meeting ends of two rails having the fish-plates B B bolted thereto. In the webs $a a$ of the rails, at the extreme ends, are made the rectangular notches $a' a'$. On the inside faces of the fish-plates B B, at their middles, are made rectangular recesses $b b$, of the same shape and size, each recess having a size equal to that of the two notches $a' a'$.

The letter C represents the supporter. This is rectangular in shape and of the size of the recesses $b b$. Its width is just sufficient to allow the fish-plates to fit the rails snugly when all the parts are in place. The supporter C is preferably made in two pieces, $c c$, made by a plane passing obliquely through the supporter, each piece being in cross section a segment of a right-angled triangle. The meeting faces $c' c'$ of the pieces are preferably roughened. Through the middle of the supporter is made a bore, d , having the countersink d' , about one-half of said bore being in each piece c . A bolt, D, passes through this bore d , its head d'' resting in the countersink d' and its threaded end d^3 protruding from the other side of the supporter, where it receives a spring-washer, e, and nut e' . When in place, the base or larger end of each piece c is to protrude somewhat beyond the smaller end of the other piece c , each base bearing against the bottom of a recess in the fish-plate, as shown in Fig. 2.

One fish-plate B is placed against the end of the rail already down. Then the supporter is placed with the countersunk side into the recess of said plate, the supporter resting in the notch a' of the rail. Then the other fish-plate is put into place, receiving the other side of the supporter C into its recess, the bolt D passing through the hole c' . The washer e and nut e' are put on. Then the other rail is slipped between the fish-plates, the recess a' coming around the supporter. Then the nut e' is firmly screwed on, drawing the two pieces $c c$ closely together and snugly fitting the supporter within the recesses $a' a'$. This produces a firm tie between the ends of the two rails, making one support the other, and also making the fish-plates help to support both. This

prevents any independent movement between the ends of the rails and makes a continuous rail the entire length of the road. As any wear takes place it is taken up by turning the 5 nut e' .

A plate, E, may be placed on the inside of the joint, said plate having a notch, f, which engages the nut e' . This plate strengthens the fish-plate at the bolt-hole, and also prevents 10 undesirable turning of the nut e' , such plate being movable in its bolt F, so that the nut e' may be reached; or, if desirable, this plate may be bolted down, as shown in Fig. 1.

In Fig. 5 is shown a modification. Here the 15 supporter C is made solid and rests in the fish-plates and recesses of the rails, but cannot be tightened to accommodate wear; or, if desirable, the supporter may be halved vertically and one half be made with each fish- 20 plate, as shown in Fig. 7.

Having described my invention, what I claim is—

1. The fish-plates having recesses and the rails having notches, in combination with an adjustable supporter placed in such recesses 25 and notches, as set forth.

2. The adjustable rail-supporter C, consisting of the parts c c' and the bolt passing through them.

3. The adjustable supporter and its bolt D, 30 in combination with the fish-plates, rails, and the plate E, as set forth.

In testimony whereof I affix my signature in presence of two witnesses.

S. ANDRAL KILMER.
